UNITED STATES PATENT OFFICE.

FRANCIS H. BROWN, OF RIDLEY PARK, PENNSYLVANIA, ASSIGNOR, BY MESNE ASSIGNMENTS, TO THE HAGAN CORPORATION, OF PITTSBURGH, PENNSYLVANIA, A CORPORATION OF PENNSYLVANIA.

CONTROLLING COMBUSTION.

Original application filed March 28, 1917, Serial No. 157,921. Divided and this application filed June 21, 1922. Serial No. 569,999.

To all whom it may concern:

Be it known that I, FRANCIS H. BROWN, residing at Ridley Park, in the county of Delaware and State of Pennsylvania, a citizen of the United States, have invented or discovered certain new and useful Improvements in Controlling Combustion, of which improvements the following is a specification.

The invention described in this application is a division of an application Serial Number 157,921, filed by me March 28, 1917, consisting of a combination of mechanisms for controlling combustion, a prominent feature of which is the automatic control of the fuel feed by means of mechanism regulated by and in accordance with variations of pressure in the furnace posterior to the bed of fuel.

The invention is designed to be utilized in conjunction with any desired type of furnace and in conjunction with any desired type of fuel, as for example, solid, liquid, or gaseous fuel, so that the introduction of such fuel to the point of combustion will be accurately controlled in accordance with the varying conditions which are taking place in the furnace.

A further purpose of this invention is to utilize in conjunction with the automatic control of the fuel feed, mechanism as for example, a stoker or its equivalent means for automatically varying the furnace pressure in accordance with the variation in load on the furnace. This load varies in character in accordance with the character of the furnace employed and in a boiler furnace the load would be the variation in the demand for steam while in a heating furnace it might be the variation in heat within the furnace.

For the purpose of illustrating my invention I have shown in the accompanying drawings typical embodiments of it which are at present preferred by me since these embodiments will give in practice satisfactory and reliable results although it is to be understood that the various instrumentalities of which the invention consists and by means of which my method can be carried out, can be variously arranged and organized and that my invention is not limited to a precise arrangement and organization of

these instrumentalities as herein shown and described.

Fig. 1 represents in sectional elevation one type of a furnace having embodied therewith my improvements in controlling mechanism, Fig. 2 represents in side elevation on an enlarged scale an automatic regulating device seen in Fig. 1; Fig. 3 shows in sectional elevation the controlling valve seen in Fig. 4; Fig. 4 shows partly in section and partly in elevation the pressure regulator seen in Fig. 1; Fig. 5 shows in side elevation another embodiment of my invention illustrating a different type of fuel feeding mechanism for feeding liquid or gaseous fuel; Fig. 6 shows a section on line VI—VI, Fig. 2; and Fig. 7 is a view similar to Fig. 1 illustrating another embodiment of my invention.

It is to be understood in carrying out my novel method in practice that I do not desire to be limited to any special type of stoker or fuel feeding mechanism, to any special type of regulator controlled by the variation in load on the furnace, to any special type of a regulator controlled by varying conditions posterior to the point of combustion, such as for example, a pressure regulator, or to the steps of utilizing natural, or mechanical draft or any special type of mechanism for controlling forced draft.

1 designates a furnace of any desired or conventional type, and as illustrated in the drawings, it is indicative of one of the individual furnaces of a battery of boilers for the generation of steam so that the load on each furnace is the variation in steam demand; 2 designates the ash pit and 3 the fuel feeding mechanism which is intended to disclose the equivalent of a stoker, and consists in a travelling grate, the movement of which is controlled by an engine 4 of any desired or conventional type and which is illustrated diagrammatically in Figure 1. It will be understood that the engine 4 is operatively connected with the travelling grate 3 in order to impart movement thereto.

5 designates a combustion chamber which is in communication with the individual stack 6, through which the products of combustion pass to the main furnace stack 7. 8 designates a boiler, in which the steam is generated, and from which it is conducted

through the dome 9 to any desired point of utilization. 10 designates a pressure regulator of the type which is now well known in the art and which may be constructed substantially in accordance with one of my prior patents, and I will therefore describe this pressure regulator with only sufficient clearness to enable one to comprehend the operation thereof.

10 11 designates a conduit which is in communication with the combustion chamber 5 and has its free end extending above the liquid in a container 12 and into the chamber 13 of an inverted tank 14. This tank 14 is located within the outer inverted tank 13 and these tanks have their lower ends sealed by the liquid in the container 12. The inverted tanks 14 and 15 are carried at one end of a lever 16 fulcrumed in any desired 15 manner and provided with an adjustable counterbalance 17. It will be understood that the buoyant action of the liquid in which the inverted tanks 14 and 15 are submerged will be lessened as the tanks are moved upward and the force of gravity will supplement the atmospheric pressure on the tanks to retard the upward movement of the tanks, and this gravitational action will increase in proportion to the upward movement of 20 the tanks.

18 designates a link which is connected with a valve 19 which controls admission and discharge of motive fluid through the pipes 20 and 21 to opposite ends of a motor 25 chamber 22, and in which is located a reciprocating piston 23. 24 designates a piston rod, the lower end of which is connected with a lever 25, which is fulcrumed on one end of a link 26, the other end of which is 30 pivotally carried by the frame or housing of the pressure regulator. The free end of the lever 25 is pivotally connected with a valve stem 27 to which is connected a valve 28 having a port 29 through its side wall. 35 This valve 28 is illustrated as a cup-shaped valve slidable in a valve casing 30 which is provided with an inlet 31 and an outlet 32. The inlet communicates by means of a port 33 with the interior of the valve casing 30 and the port 29 registers at times with the 40 port 33. The valve 28 is shown as a cup-shaped valve having the ports 34 through one end to balance the pressure of motive fluid against the valve. The inlet 31 communicates by means of a valve controlled 45 conduit 35 with the steam dome 9. The outlet 32 communicates by means of a valve controlled conduit 36 with the engine 4. The piston rod 24 of the pressure regulator 50 10 has connected to its upper end a cable 37 which passes over pulleys 38 and is connected to a damper 39 in the auxiliary draft conduit 40 which communicates with the ash-pit 2. The damper 39 is provided with 55 an adjustable counterbalance 41. The aux-

iliary draft conduit 40 communicates with the main draft conduit 42 which is in communication with each furnace of the battery. The furnace may be operated under either a natural or forced draft and I have 70 illustrated in Figure 1 a draft conduit 43 for the natural draft so that when the damper 44 is closed, the furnaces will operate under natural draft. When the damper 44 is opened, as indicated in dotted lines in Figure 1, the blower 45 is in communication with the main draft conduit 42 so that the furnaces will operate under forced draft. The blower 45 is intended to illustrate the conventional type of forced draft wherein 75 the blower is actuated by an engine 46 which is provided with a governor 47, so that the speed of the engine can be automatically controlled.

Each individual stack 6 is provided with 80 a damper 48 having a counterbalance 49 and provided with a cable 50 which extends into a position accessible to the engineer in order to provide for the manual control of the damper 48. Each individual stack 6 is provided with an automatically controlled damper 51 which is provided with a pulley 52 around which passes a cable 53, which is provided with a counterbalance 54, said counterbalance being adjustable. The cable 53 is connected to a piston rod 55 of a motor 56. The admission and exhaust of motive fluid to the motor 56 is controlled by means of a pilot valve 57 and the stem of the valve, as indicated by 58, is connected to a lever 59 to which is pivoted an adjustable connection 60, the other end of which is connected with a lever 61. The lever 61 is provided with an adjustable counterweight 62 and an adjustable counterbalance 63. The lever is 100 actuated by a diaphragm motor 64 of any conventional type, one side of which is subjected to variations in steam pressure which is introduced into proximity to said diaphragm through a steam conduit 65 which is in communication with the steam dome 9. The lever 59 is connected by means of a link 66 with an elbow lever 67 which is fulcrumed to a fixed point. This elbow lever 67 carries at one end a shoe 68 which is slidably mounted upon a guide 69 pivoted at its lower end to a fixed point as 70, on a bracket 71 which is adjustably fixed to the piston rod 58 which is connected to the cable 53. The upper end of the bracket 71 is provided with a worm 72 adapted to be manually adjusted and which meshes with a rack 73 at the upper end of the guide 69 in order to provide for the angular adjustment of the said guide 69. This bracket 71 and its adjuncts form a compensating mechanism, so that a graduated adjustment of the damper 51 is automatically provided in accordance 110 with variations in the steam pressure.

115 It will be seen from Figure 6 that the shoe 120

68 is pivotally carried by the bifurcated end of the lever 67.

In Fig. 1 I have illustrated the mechanism for providing an automatic control of the fuel feeding mechanism which can be employed in case a solid fuel is used, and in Figure 5, I have illustrated a typical mechanism which can be employed in case a liquid or gaseous fuel is used. The cable 37 in Figure 5 would be connected to the pressure regulator 10 and controls the auxiliary draft conduit 40 to the individual furnace in the same manner as already described with reference to Figure 1, and I have therefore identified the corresponding parts by the same reference characters. Connected to the cable 37 is a cable 74 which passes around a controlling valve 75 and is provided with a counterbalance 76. The valve 75 automatically controls the passage of fuel of a liquid or gaseous nature through the nozzle or injector 77. The other parts of the mechanism for controlling combustion would correspond to the typical mechanism illustrated in Fig. 1.

The operation of my novel apparatus will now be readily understood by and apparent to those skilled in the art to which this invention appertains and is as follows:—

The furnace can be operated under either natural or forced draft, and the mechanism for producing the forced draft is preferably automatically regulated. As the demand for steam increases, or in other words, the load on the individual furnace, the diaphragm motor 64 is actuated to control the pilot valve 57 to thereby admit motive fluid to the motor 56 to cause the damper 51 to move in the direction of opening and thereby decrease the pressure posterior to the point of combustion, such as for example as the furnace pressure in the combustion chamber since such combustion chamber is now in communication with the atmosphere through the stack 6 of the individual furnace. This change in pressure causes the lever 16 to be actuated to operate the pilot valve 19 and admit motive fluid to the motor 22 and thereby actuate the piston rod 24. The piston rod 24 will move downwardly thereby causing the lever 25 to move the valve stem 27 upwardly, and steam is permitted to pass from the conduit 35 through the inlet 31, the ports 33 and 29, through the port 32 into the conduit 36 and thence to the engine 4 to cause the fuel to be fed into the furnace. This downward movement of the piston rod 24 actuates the cable 37 to open the valve 39 and permit the draft for combustion to pass from the main draft conduit 42 into the ash-pit 2 of the individual boiler.

In order to illustrate the one manner of carrying out my method, I have preferred to show a single instrumentality for simultaneously controlling the operation of the fuel feeding mechanism and the introduction of draft for combustion, but it is to be understood that it is within the scope of my invention to employ separate mechanisms for such control in accordance with conditions and requirements met with in practice. When the load on the furnace decreases, such for example, a decrease in the demand for steam, the motor 56 will be actuated to cause the damper 51 to close to a degree corresponding to the change in steam pressure, and the fuel feeding mechanism and the primary draft will be correspondingly actuated to decrease the amount of fuel being fed and the amount of air introduced for combustion. Owing to the provision of the compensating mechanism which is best illustrated in Figures 2 and 6, the damper 51 is not moved to a fully open or closed position on the variation in steam pressure but a graduated movement is provided. The bracket 71, carried by the piston rod 55 as it moves in one direction or the other, actuates the shoe 68 to move the valve stem 58 and correspondingly control the pilot valve 57. It is not essential in all cases arising in practice to use all of the steps of my method as herein set forth and they can be used alone and independently of each other or in any combination.

In so far as I am aware, I am the first in the art to devise the step of automatically controlling the fuel feed by variations in furnace conditions posterior to the point of combustion, such as for example, the variations in the furnace pressure. I am also the first in the art, in so far as I am aware, to employ in conjunction with such step, the automatic control of the primary draft in accordance with varying conditions posterior to the point of combustion, either alone or in conjunction with the step of automatically varying conditions posterior to the point of combustion in accordance with variations in load on the furnace or furnaces. It is therefore to be understood that my claims to such features are to be interpreted with the scope to which a generic invention is entitled.

In some cases arising in practice, the damper 51 and its adjuncts may be dispensed with and the damper 48 can be manually controlled to vary the conditions of pressure posterior to the point of combustion.

Another embodiment of my invention is seen in Fig. 7 wherein instead of controlling the damper 51 by variations in steam pressure, it is controlled by variations in furnace conditions posterior to the point of combustion, such as for example, the furnace pressure. In this embodiment, the steam regulator seen in Fig. 2 is dispensed with, and the cable 37 is connected to or forms a part of the cable 53 which controls the

damper 51 in the stack of its respective furnace. In carrying out the method disclosed in this embodiment seen in Fig. 7, as soon as the pressure in the furnace increases to a 5 predetermined point, it will actuate the stack damper and also actuate the controlling means for controlling the introduction of fuel. It is to be understood that in conjunction with this embodiment seen in Fig. 7, 10 I dispense with the damper 39 and its automatic control, and the engine is automatically controlled by steam passing from the dome 9 through the conduit 78, the by-pass 79 and the steam regulating valve 80, the 15 valve 81 being closed and the valves 82 opened and the governor being disconnected. In the method first described in connection with Figure 1 the valve 82 would be closed and the valve 81 would be open. In 20 accordance with my present invention, one is enabled to maintain a constant rate of combustion in each furnace, irrespective of the thickness of the bed of fuel or the resistance offered to the draft.

25 It will now be apparent that I have devised a new and useful method of controlling combustion, which embodies the features of advantage enumerated as desirable in the statement of the invention and the above description, and while I have, in the present instance, shown and described typical embodiments thereof which will give in practice satisfactory and reliable results, it is to be understood that these embodiments are 30 susceptible of modification in various particulars without departing from the spirit or scope of the invention or sacrificing any of its advantages.

I claim herein as my invention:

40 1. The method of controlling combustion in a furnace which consists in automatically controlling the source of supply of the forced draft for combustion, and automatically controlling the fuel feed and 45 the discharge of products of combustion from the furnace by variations in furnace conditions posterior to the point of combustion.

50 2. The method of controlling combustion in a furnace which consists in automatically controlling the source of supply of a forced draft for combustion, and automatically controlling the fuel feed and the discharge of 55 products of combustion from the furnace by variations in furnace pressure.

60 3. The method of regulating furnaces which consists in maintaining in the furnace chamber a substantially uniform pressure under varying rates of combustion, and 65 in regulating the resistance of the fuel bed to bear any desired relation to the rate of combustion by controlling the rate of feed of fuel in accordance with variations in the means for maintaining in the furnace a substantially uniform pressure.

4. The method of regulating furnaces which consists in maintaining in the furnace chamber a substantially uniform pressure under varying rates of combustion and in automatically regulating the resistance of the fuel bed to bear any desired relation to the rate of combustion by controlling the rate of feed of fuel in accordance with variations in the means for maintaining in the furnace a substantially uniform pressure. 75

5. The method of regulating furnaces which consists in maintaining in the furnace chamber a substantially uniform pressure under varying rates of combustion, and in regulating the resistance of the fuel bed to correspond to different rates of combustion by controlling the rate of feed of fuel in accordance with variations in said means for maintaining in the furnace a substantially uniform pressure. 80

6. The method of regulating furnaces which consists in maintaining in the furnace chamber a substantially uniform pressure under varying rates of combustion, and in automatically regulating the resistance of the fuel bed to correspond to different rates of combustion by controlling the rate of feed of fuel in accordance with variations in said means for maintaining in the furnace a substantially uniform pressure. 90

7. The method of regulating furnaces which consists in maintaining in the furnace chamber a substantially uniform pressure under varying rates of combustion and in regulating the rate of feed of fuel in accordance with variations in the means for maintaining in the furnace a substantially uniform pressure, and in such manner that the rate of feed of fuel will vary inversely as to variations in relation of fuel bed resistance to rate of air supply, and directly as to the rate of air supply. 100

8. The method of regulating furnaces which consists in maintaining in the furnace chamber a substantially uniform pressure under varying rates of combustion and in automatically regulating the rate of feed of fuel in accordance with variations in the means for maintaining in the furnace a substantially uniform pressure, and in such manner that the rate of feed of fuel will vary inversely as to variations in relation of fuel bed resistance to rate of supply, and directly as to the rate of air supply. 110

9. The method of regulating furnaces which consists in maintaining in the furnace chamber a substantially uniform pressure under varying rates of combustion, and in regulating the rate of feed of fuel in accordance with variations in the means for maintaining uniform pressure under varying rates of combustion so that the rate of feed of fuel will vary inversely as the resistance of the fuel bed, and directly as the rate of supply of air to the furnace. 120

10. The method of regulating furnaces which consists in maintaining in the furnace chamber a substantially uniform pressure under varying rates of combustion, and in 5 automatically regulating the rate of feed of fuel in accordance with variations in the means for maintaining uniform pressure under varying rates of combustion, so that the rate of feed of fuel will vary inversely as 10 the resistance of the fuel bed, and directly as the rate of supply of air to the furnace.
11. The method of operating boiler furnaces which consists in maintaining a substantially uniform furnace gas pressure for 15 varying rates of combustion and regulating the rate of fuel feed in accordance with the rate of outflow of the furnace gases.
12. A boiler furnace having in combination therewith air impelling means for supplying 20 draft thereto, a stoker for feeding fuel to the furnace regulating means for maintaining the pressure of the furnace gases substantially uniform for varying rates of combustion, and means whereby the stoker is 25 controlled by said regulating means.
13. A boiler furnace having in combination therewith means for feeding fuel thereto, regulating means for maintaining the pressure of the furnace gases substantially 30 uniform for varying rates of combustion, and means whereby the fuel feeding means is controlled by said regulating means.
14. A boiler furnace having in combination therewith air impelling means for supplying draft thereto, a stoker for feeding fuel to the furnace, regulating means for maintaining the pressure of furnace gases substantially uniform for varying rates of combustion, and means whereby the speed of the stoker is controlled by said regulating 35 means. 40
15. A furnace having in combination therewith a stoker for feeding fuel thereto, a regulator acting in response to fluctuations of pressure of furnace gases to render said pressure uniform, and fuel feeding means for the furnace controlled by said regulator. 45
16. A furnace having in combination therewith a stoker for feeding fuel thereto, air impelling means for furnishing draft, 50 means for controlling the air impelling means by the steam pressure of the boiler, means for controlling the stoker in accordance with the variations of the air impelling means, and means for maintaining substantially uniform pressure in the furnace for varying rates of combustion which last named means also varies the relative speed of the stoker to that of the air impelling means. 55
- 60

In testimony whereof, I have hereunto set my hand.

FRANCIS H. BROWN.
